UNITED STATES PATENT OFFICE.

JAMES ASPDEN, OF CAMDEN, NEW JERSEY.

SEPARABLE BOAT.

SPECIFICATION forming part of Letters Patent No. 449,241, dated March 31, 1891.

Application filed July 9, 1890. Serial No. 238,145. (No model.)

To all whom it may concern:

Be it known that I, JAMES ASPDEN, a citizen of the United States, and a resident of the city and county of Camden, and State of New Jersey, have invented certain new and useful Improvements in Separable Boats, of which the following is a specification.

My invention relates to improvements in boats; and the object of my invention is to furnish a separable boat which may be readily taken apart or put together. My separable boat is particularly intended for use upon streams which are navigable only in times of freshets. It may be taken apart and carried to the head-waters of the stream by wagon or other conveyance, when it may be put together and loaded, and at a suitable stage of water it may be floated downstream to its destination, when the cargo may be discharged and the boat taken apart again and returned in pieces to its starting-point. My separable boat is also well adapted for shipment to places difficult of access or to foreign countries.

In the accompanying drawings, forming part of this specification, and in which similar letters of reference indicate similar parts throughout the several views, Figure 1 is a plan of my separable boat; Fig. 2, a section of Fig. 1 on line 1 2, and Fig. 3 a section of Fig. 1 on line 3 4.

The form of my boat is that commonly called a "scow." It has a flat bottom, square ends, and straight sides.

The bottom of the boat is constructed of a number of tongue-and-grooved planks *a*, which preferably run thwart-ways of the boat. The sides of the boat are constructed of tongue-and-grooved planks *b*, which run fore and aft of the boat, and the ends are constructed of similar planks *c*, which extend from one side to the other.

d are rods running lengthwise of the boat and near its bottom, and which pass through the ends *c* of the boat. The ends of these rods are threaded, and *e* are nuts placed upon them, and which bear against ends *c* of the boat and by means of which these ends may be drawn in, so as to bear firmly against the bottom boards *a*. The rods *d* pass through screw eyes or staples *d'*, which are secured to the bottom boards *a*. These screw eyes or staples

and rods *d* keep the bottom perfectly straight while being drawn together and prevent the boards *a* from springing at their joints.

f are rods running lengthwise of the boat, 55 and which pass through the ends *c*. The ends of these rods are threaded, and *g* are nuts upon them, which bear against the ends of the boat.

In the drawings I have shown but two rods 60 *f* upon each side of the boat, one near the bottom and the other near the top; but it will be understood that any number of intermediate rods may be used, if desired.

The sides of the boat are drawn toward 65 each other and against the bottom and ends by rods *h* near the bottom of the boat, and by rods *i* near its top, and by intermediate rods, if necessary. These rods *i* are furnished with nuts similar to those upon the longitudinal rods *d*.

The bottom boards *a* of the boat project some little distance beyond the sides *b* and have channels cut into them to receive the sides *b*, as shown in Fig. 2.

j are rods, the ends of which are bent over the top of the sides *b*, and which extend down along these sides and pass through the bottom boards *a*. The lower ends of these rods are threaded and furnished with a nut *k*, which 80 bears against the bottom boards *a*. By means of nut *k* and rod *j* the boards *b*, forming the sides of the boat, may be drawn together, in order to make tight joints to exclude the water.

In order to insure the joints between the 85 several boards forming the boat being perfectly water-tight, they are covered, before being put together, with white lead, pitch, or some other similar and suitable substance, and, if necessary, a packing of some fibrous 90 material—for instance, cotton or oakum—may also be placed between them.

The boat may be readily and quickly taken apart for purposes of land transportation by unscrewing the nuts from the several rods 95 which hold it together, and it may be easily and rapidly put together again.

A figs. 1 and 2, is a timber which runs lengthwise of the boat and which is bolted to the several boards forming the bottom. In 100 narrow boats this timber would not be necessary; but in broad ones it would be desirable,

as it would stiffen the planks of the bottom. One or more of these timbers may be used, as the size of the boat and the thickness of planking might require.

5 In Fig. 2 I have shown the boat furnished with buoys B upon its sides, which are intended to increase the carrying capacity of the boat, as well as its stability. These buoys may be of any desired length or thickness and are secured to the sides of the boat by straps C.

10 D is a tilting table, which is hinged to one side of the boat by hinges E. This table has at its outside end raised sides F, which are furnished with perforations G. The table is intended for use when the boat is being used 15 as a tender for a dredging-machine. The contents of the bucket are first emptied upon the table and the water runs off through the holes or perforations G, after which the table 20 is tilted and its contents are emptied into the boat.

Having thus described my invention, I claim—

1. The herein-described separable boat, consisting of a bottom constructed of tongue-and-grooved planks, in combination with ends and

sides, substantially as described, and rods and nuts by means of which the bottom, sides, and ends are held together.

2. In a separable boat and in combination, 30 the bottom, sides, and ends formed of tongue-and-grooved planks and adapted to be caulked when put together, as described, and the longitudinal and transverse rods and nuts by means of which the several planks forming the boat are held in place, substantially 35 as described.

3. In combination with the bottom planks a, end pieces c, and rods and nuts for drawing these planks and end pieces together, the 40 screw eyes or staples d', secured to said planks a, and through which said rods pass, substantially as and for the purposes set forth.

4. The combination, with a boat, of a tilting table hinged to the sides of the boat and 45 furnished with perforated raised sides at its outer end, as and for the purposes set forth.

JAMES ASPDEN.
